UNITED STATES PATENT OFFICE.

WILLIAM S. PARKER, OF ROCKFORD, ILLINOIS, ASSIGNOR TO BURSON KNITTING COMPANY, OF ROCKFORD, ILLINOIS, A CORPORATION OF ILLINOIS.

KNITTING MACHINE.

Application filed August 20, 1923. Serial No. 658,250.

This invention relates to straight knitting machines, and has more particular reference to the needle-supporting and actuating mechanism.

5 Heretofore, in machines of this type having opposed flat beds of needles, it has been customary to move each needle in the knitting operation by means of a jack and to move each jack into and out of operative relation to a needle-actuating cam by means of a jack lever in turn operated and controlled by a pattern cylinder. In practice, it is found very difficult to obtain a high degree of accuracy and precision in the operation of the needles, due to small dimensional variances in the manufacture of these co-operating parts and also to the wear between such parts, which causes lost motion and slight irregularities in the operation of 15 the needles. These slight irregularities appear in the quality of the knitted fabric, making it difficult to obtain the desired uniformity and fine grade of goods knit on these machines.

25 The primary object of the present invention is therefore, to improve the grade and quality of knitting on machines of this kind by the provision of an improved needle supporting and operating mechanism. This 30 mechanism comprises fewer parts so constructed as to obviate the objectionable features of the above-mentioned jack-operated needles.

More particularly, I have provided an 35 improved means for supporting the needles and for moving them into and out of operative relation to the needle-actuating cams. In this construction, each needle is slidable on a supporting part which is pivoted near 40 the throat of the machine and operated by a pattern cylinder lever for moving a projection on the needle into and out of the path of the needle-actuating cam.

It is also contemplated to provide an improved bed construction especially adapted to my present improvements, as will be presently apparent.

Other objects and attendant advantages will be appreciated by those skilled in this 50 art as the invention becomes better understood by reference to the following description when considered in connection with the accompanying drawings, in which—

Figure 1 is a fragmentary top view of a

straight knitting machine embodying my 55 invention; and

Fig. 2 is a vertical sectional view taken substantially on the line 2—2 of Fig. 1.

In some respects the machine illustrated herein is similar to the Burson type of 60 straight bed knitting machines, as, for example shown in U. S. Letters Patent #616,600. The well-known parts comprise the pattern cylinders 3 and 4, yarn carrier guides 5, presser hooks 6, the beds 7 and 65 cams 8 for the presser hooks, and slides 10 equipped with the needle-actuating cams 9.

The needle bed and appurtenant parts at each side of the machine being identical, a description of one will suffice. The bed is 70 of a laminated construction, composed of movable needle supports 11 and stationary supports 12 arranged in alternation on a plurality of horizontal bed rods 13, 14 and 15. The needle-supporting members 12, 75 preferably pressed from sheet metal, are held in rigid relation by comb bars 16, 17, 18, 19 and 21, these bars and the bed rods being rigidly secured to end frames or standards, not shown. These bars and rods 80 are sufficiently heavy to carry without deflection or vibration the laminated bed structure and other parts carried thereby.

Each needle 22 has a relatively long shank, a projection 23 near its butt end, 85 and an extended butt end 24. The needle is slidably supported on the top surface 25 of the support 11 and receives side support from the adjoining members 12. A suitable spring 26 urges the hook end of the needle 90 down on its support, giving proper tension to the needle, and the butt end 24 is adapted to engage beneath the over-reaching portion 27 on the support 11 when the needle is retracted, so that it will be carried with said 95 support when it is moved as will be presently described.

Each needle support 11 is pivotally mounted on a rod 28 positioned adjacent to the throat of the machine, thus permitting the 100 support to be moved vertically at its outer end for raising the needle projection 23 into and out of operative relation to the cam 9. When the support 11 is raised, as shown, the needles will be in action, the needle projections 23 being directly operated by the 105 cams 9 for advancing and retracting the needles, thus eliminating a source of error

which invariably results from the use of a multiplicity of parts and motion-transmitting contact points between the cam and each needle. When the support 11 is lowered, its 5 needle projection 23 will obviously be withdrawn from the path of the cam, thus holding the needle out of action.

Each needle support 11 is independently operated by a lever 29 interposed between the 10 adjoining supporting members 12 and directly operated by the adjacent pattern cylinder. The lever pivotally mounted at 31 and having pattern followers 32, 33 and 34, has a pivotal connection with its needle 15 support 11, consisting of a circular portion 35 fitting in a circular recess 36 in the support 11, this recess being slightly elongated in the direction of a line connecting the pivots 28 and 31 to prevent binding between 20 the connected parts. The cam plates of the laminated pattern cylinder are so shaped as to rock the lever 29 in opposite directions for raising and lowering the needle supports 11, these pattern cam plates being shown but 25 briefly herein as their construction is well understood in this art.

It will be manifest from the foregoing that the needles are moved by a very simple and directly operating mechanism into and 30 out of action, and that the construction by reason of its direct action is such as to promote greater uniformity in the knitting operation and consequently improve the quality of knitting.

35 It is believed that the foregoing conveys a clear understanding of the objects pref-

aced above, and while I have illustrated but a single working embodiment it should be understood that changes may be made in the construction and arrangement of parts without departing from the spirit and scope of the invention as expressed in the appended claims.

I claim:

1. In a knitting machine, the combination 45 of the needles, each having a projection near its butt end, a needle-actuating cam for operating said projections, a support for each needle pivoted near the throat of the machine and having a recess therein, pattern 50 mechanism, and a lever for each support operated by the pattern mechanism and having a circular end fitting in said recess, whereby the needle supports will be operated by the levers for moving the needles into 55 and out of operative relation to the cam.

2. In a knitting machine, the combination 60 of needles each having an operating projection thereon, a needle actuating cam engaging the same, a support for each needle pivoted near the throat of the machine, pattern mechanism, and a lever for each support operated by the pattern mechanism, each lever and its associated support having an operating connection consisting of a recess 65 provided on the one part receiving a projection provided on the other part, whereby the needle supports are operated by the levers for moving the needles into and out of operative relation to the cam.

WILLIAM S. PARKER.
